UNITED STATES PATENT OFFICE.

WILLARD C. COOK, OF CLOVIS, CALIFORNIA.

DESIGN FOR A FRUIT BASKET.

Application filed May 15, 1924. Serial No. 9,600. Term of patent 7 years.

To all whom it may concern:

Be it known that I, WILLARD C. COOK, a citizen of the United States, and a resident of Clovis, county of Fresno, State of California, have invented a certain new, original, and ornamental Design for a Fruit Basket, of which the following is a specification, reference being had to the accompanying drawings, forming part thereof.

Fig. 1 is a side elevation of the fruit basket.

Fig. 2 is a side elevation of the fruit basket, looking at right angles to Fig. 1.

Fig. 3 is a top plan view of the fruit basket.

Fig. 4 is a bottom plan view of the fruit basket.

I claim:

The ornamental design for a fruit basket, as shown.

In testimony whereof I have signed this specification at San Francisco, California, this 10th day of May, 1924.

WILLARD C. COOK.
